FOLDABLE BOAT

Donald G. Jackson, Pasadena, Calif.

Application August 2, 1946, Serial No. 688,007

25 Claims. (Cl. 9—2)

1

This application is a continuation-in-part of my prior application Serial No. 499,038, filed August 18, 1943 now abandoned, and relates to a boat of a semi-rigid foldable type adapted to be folded into compact form for transportation and storage purposes.

One object of this invention is to provide a foldable boat of sturdy, light-weight construction which is strong and safe, being capable of supporting considerable weight without collapsing or springing out of shape.

Another object is to provide a boat of the character referred to which comprises a rigid bottom or floor, a rigid top or gunwale and a flexible waterproof cover secured between the floor and gunwale and providing therewith the sides, bow and stern of the boat.

Another object is to provide a boat of the type indicated wherein the floor and gunwale are each made in two halves or sections pivoted together transversely of the theoretical keel of the boat to adapt them to be relatively pivoted into overlying relationship with the flexible cover folded therebetween to reduce the length of the boat to one-half its extended length and substantially reduce the height thereof whereby to provide a bundle of compact form which may be readily transported and stored.

Another object is to provide a boat of the type specified in which bracing struts are pivoted to the floor sections and including operating means responsive to movement of said floor and gunwale sections to open position for automatically pivoting said struts into operative position between the floor and gunwale to force them apart and stretch the flexible cover therebetween and operative upon pivotal movement of said sections to folded position to release the struts to permit them to pivot to inoperative position. This arrangement of parts permits automatic forming of the boat by the simple act of unfolding the floor and gunwale sections.

Another object is to provide a folding boat including means associated with the bracing struts and movable therewith to provide seats within the boat, said seats being disposed between the floor sections and gunwale sections when the several sections are folded into overlying relationship.

Another object is to provide in a boat of the type identified locking means for locking the floor sections in extended position to add rigidity thereto and positively guard against collapsing of the boat.

2

Another object is to provide a foldable boat in which all of the parts are connected to provide a unitary structure thereby avoiding the use of separable elements which are apt to become disconnected and lost and which must be separately installed when the craft is to be used.

Another object is to provide a foldable boat which is extremely simple in construction, being composed of a minimum number of parts adapted for economical manufacture and one which is highly efficient and durable in use.

Further objects of my invention are set forth in the following specification and the drawings which are intended for the purpose of illustration only, and in which:

Fig. 1 is a plan view of my improved foldable boat;

Fig. 2 is a longitudinal sectional view through the boat;

Fig. 3 is a view similar to Fig. 2 but illustrating the boat in partly folded condition; and

Fig. 4 is an enlarged longitudinal section of the mid-portion of the boat showing a modified form of strut-operating means.

25 My improved foldable boat comprises, in general, a bottom or floor composed of rigid fore and aft sections pivoted together on an axis extending transversely of said boat, a gunwale composed of rigid fore and aft sections pivoted together on an axis extending transversely of said boat, a waterproof flexible cover extending between the floor and gunwale and forming therewith the sides, bow and stern of said boat, strut members pivoted to the floor sections and adapted to be pivoted into engagement with said gunwale to maintain the floor and gunwale in spaced relationship, and to stretch said flexible cover therebetween, operating means responsive to folding and unfolding said floor and gunwale sections to automatically operate said strut members, and locking means for locking the floor sections in unfolded relationship.

Referring to the drawings in detail, my foldable boat comprises a bottom or floor, indicated generally by the reference character 10, which consists of a rigid fore section 11 and a rigid aft section 12. The floor sections 11 and 12 meet at a line 13 extending transversely of the boat substantially midway between its forward and rearward ends. Fastened to the sections 11 and 12 adjacent their inner abutting edges are blocks 15 and secured to the upper surface of the blocks are the opposite leaves 16 and 17 of flap hinges 18. Through this construction, the fore and aft

floor sections 11 and 12 are adapted to be pivoted on the hinge pins 19 into overlying relationship for the purpose to be explained hereinafter.

The boat also includes a gunwale 20 consisting of a rigid fore section 21 and a rigid aft section 22 which are pivotally connected together on a line 23 extending parallel to and above the parting line 13, previously mentioned, by means of flap hinges 25 having hinge pins 26.

The floor 10 and gunwale 20 may be of any desired configuration, the present drawings illustrating these parts as provided with a relatively pointed nose or bow 28 and a substantially square stern 29. Secured to the outer lateral edges of the gunwale 20 and floor 10 in any suitable manner is a strip or cover 30 of waterproof flexible material such as duck, canvas, or neoprene impregnated fabric. The cover 30 thus follows the contour of the perimeters of the gunwale 20 and floor 10 and the ends of the strip are suitably joined in a leak-proof seam as indicated at 31. The cover 30 thus defines, with the gunwale 20 and floor 10, the sides, bow and stern of the boat and its height determines the height of the craft. At the opposite sides of the boat where the fore and aft sections meet the cover 30 is formed with small vertically extending loose folds 33 for the purpose of providing additional material at the hinged joints of the floor 10 and gunwale 20 to permit relative pivotal movement of the floor and gunwale sections without unduly stretching the cover material. A strip of waterproof material is also secured to the bottom of the floor sections 11 and 12 adjacent the parting line 13 and this strip is folded into the interior of the boat as shown at 34 to provide an effective sealing means between the two floor sections, the strip 34 being joined to the fold 33 in any suitable manner. The folded sealing strip 34 is adapted to open out when the two floor sections 11 and 12 are relatively pivoted to overlying relationship.

Fastened to the upper surfaces of the floor sections 11 and 12 are yoke-like brackets 40 carrying pivot pins 41. Four of such brackets 40 are mounted on each floor section 11 and 12 and are arranged in pairs disposed adjacent the sides of the boat. Pivoted on the pins 41 within the forward portion of the boat are forward and rearward pairs of bracing arms or strut members 43 and 44. Mounted for pivotal movement on the pins 41 within the rearward portion of the boat are similar forward and rearward pairs of strut members 45 and 46. The several strut members 43, 44, 45 and 46 carry pivot pins 47 substantially midway between their ends and pivotally connected to the pins are the opposite ends of forward and rearward links or connecting members 48 and 49. The links 48 in the forward portion of the boat are connected by a horizontal plate 50 which provides the forward seat of the boat. The links 49 in the rearward portion of the boat are similarly connected by a plate 51 constituting the rear seat of the boat.

When the parts of the boat are in unfolded or extended position the strut members 43, 44 and 45, 46 are held in the inclined positions shown in Fig. 2 and their free ends engage the underside of the gunwale sections to spread the floor 10 and gunwale 20 apart and to stretch the canvas cover 30 therebetween. The strut members 43, 44 in the forward portion of the boat and the strut members 45, 46 in the rearward portion of the boat are automatically pivoted to operative position by pairs of operating members or ties 55 and 56, respectively. As shown in Figs. 1 and 2,

5 the operating members 55 and 56 may comprise straps or other flexible means such as a chain or cable. One end of each strap 55 is suitably joined to the rearward strut members 44, preferably at their pivot pins 47, while the other end of each strap 55 is connected to a loop element 60 fastened to the aft floor section 12. In a like manner, one end of each strap 56 is joined to the forward strut members 45 while its other end is connected to a loop element 61 fastened to the fore section 11 of the floor 10.

10 It will be apparent that through the arrangement of parts described above the several strut members are automatically swung upwardly during the unfolding of the floor and gunwale sections 11, 12 and 21, 22 to operative or extended position. The strut members thus serve to brace the structure to prevent collapse thereof. It is necessary however, that the fore and aft sections 15 of the boat be locked in extended position since it is obvious that if the sections were permitted to pivot, the straps 55 and 56 would no longer retain the strut members in operative position. As a means for positively locking the boat sections 20 in extended relationship I prefer to employ 25 a drawbar 64 which is slidable in aligned loops or eyes 65 on the floor sections 11 and 12. With the drawbar 64 inserted through the loops relative pivotal movement between the floor sections 30 is prevented and thus the parts are maintained 35 in the extended relationship shown in Fig. 2. The straps 55 and 56 may have a looped end with the sides of the loop joined by a buckle so that tension of the belts may be readily adjusted. In 40 lieu of the straps 55 and 56, operating rods 70 such as shown in Fig. 4 may be advantageously utilized. In this embodiment each rod 70 may consist of two sections 71 and 72 connected by turnbuckles 73 to adjust the overall length of the rods.

To aid further in bracing the structure to safeguard against collapse of the boat, brace members or props 75, 76, 77 and 78 may be employed. The brace member 75 is pivoted to the bow end 45 of the gunwale section 21 and is adapted to be pivoted downwardly into engagement with the floor section 11 to serve as a spacing and stiffening means. The prop 76 is hinged to the forward seat 50 and may be swung downwardly with its 50 lower end resting against the floor section 11 to prevent lowering of the strut members 43, 44 and to provide a support for the seat. The prop 77 is hinged to the rear seat 51 and engageable with the aft floor section 12 and thus braces and 55 adds rigidity to the rear portion of the boat and adapts the rear seat to support considerable weight. The parts at the stern of the boat are braced by the member 78 which is hinged to the transversely extending portion of the gunwale 20 and adapted to engage against the floor section 12 60 when pivoted down as shown in Fig. 2. It is thus seen that the various sections of the boat are firmly braced to permit the boat to withstand considerable strains and stresses caused by the application of weight and waves upon which the boat is riding.

65 My foldable boat may be used either as an oar-propelled or motor-propelled craft. Socket members 80 may be provided on the gunwale 20 for receiving car-locks 81, indicated by dotted lines in Fig. 2, in which the oars (not shown) may be supported. The stern portion of the gunwale 20 is recessed as shown at 82 in Fig. 1 to adapt an outboard motor (not shown) to be mounted 70 thereon in the usual manner with the motor cas-

ing resting against the member 78. A strap 84 having its buckle end fastened to one side of the fore gunwale section 21 is adapted to encircle and tie the several sections 11, 12, 21, and 22 together when the latter are folded into a compact bundle in the manner to be later explained. The floor sections 11 and 12 and the gunwale sections 21 and 22 are preferably constructed from plywood and the connecting members 48, 49, strut members 43, 44, 45, 46 and the brace members 75, 76, 77, 78 may be fabricated from hard wood. It is to be understood, however, that other materials, such as light weight metals or plastics may be employed with equal success. I have found that when the boat is constructed approximately nine feet long, three feet wide and fourteen inches high it weighs approximately sixty pounds and thus may be easily propelled and steered in the water and conveniently handled. A boat of these dimensions may be folded into a compact bundle approximately four and one-half feet long by three feet wide by five inches thick which may be readily transported within an automobile.

My improved foldable boat is operated in the manner next explained. Assuming that the parts of the boat are in the positions illustrated in Figs. 1 and 2, that is, in fully extended relationship the boat is ready for use and may be rowed or motor-propelled as desired. Because of its light weight, the boat may be readily moved through the water with a minimum of effort on the part of the rower or with minimum power when an outboard motor is employed and may be easily maneuvered. In this respect, it is pointed out that the floor or bottom 10 of the boat may be provided with a keel, if desired.

After the boat has been used and it is desirable to transport or store it for future use it is folded into small compass in the manner next explained. To fold the boat, the drawbar 64 is first withdrawn from the loops 65 and thereafter the props 75, 76, 77 and 78 are pivoted upwardly as indicated by dotted lines in Fig. 2. With the various parts thus unlocked, one of the floor sections 11 or 12 is raised and swung over upon the other section. Simultaneous with this pivotal movement the gunwale sections 21 and 22 will also be folded in the manner of a hinge as shown in Fig. 3. As the floor sections 11 and 12 are thus pivoted the tension on the straps 55 and 56 will be relieved so that the strut members 43, 44, 45 and 46, together with their connecting members and seats 50 and 51 may pivot down against the floor sections 11 and 12. The result of this pivotal movement of the strut members is to permit the gunwale sections 21 and 22 to be nested within the floor sections 11 and 12 to substantially reduce the height of the boat. During the folding of the boat sections the flexible cover 30 may be tucked in between the sections to prevent damage thereto during transportation of the boat. The looped sealing strip 34 will be automatically withdrawn from a position between the floor sections 11 and 12 and will straighten out to accommodate the pivotal movement of the sections. After the boat has been folded and collapsed the strap 84 may be tightened around the parts to retain them in compact form.

To unfold the boat the steps outlined above are reversed. That is to say, the strap 84 is first removed and with the folded boat standing on the edge of its mid-portion as shown in Fig. 3, the fore and aft portions are opened and hinged downwardly with the floor sections 11 and 12 pivoting on their hinge pins 19 and with the gunwale sections 21 and 22 pivoting on their hinge-

pins 26. During the opening of the boat sections the sealing strip 34 will fold in between the sections 11 and 12 and the straps 55 and 56 will be drawn taut to cause the strut members 43, 44, 45 and 46 to pivot away from the floor sections 11 and 12 and to assume the inclined positions shown in Fig. 2. It is apparent therefore that the free ends of the strut members will engage the under sides of the gunwale sections 21 and 22 and act to spread the floor and gunwale sections apart and tension the flexible cover 30 therebetween. With the boat thus shaped, the props 75, 76, 77 and 78 are lowered into engagement with the floor sections to provide rigidity and prevent collapsing of the boat. The drawbar 64 then is slid through the loops 65 to lock the boat sections in extended position. When the boat is provided with the operating rods 70 shown in Fig. 4 it is necessary to divide the rods into two parts to permit pivotal movement of the boat sections and this may be readily accomplished by rotating the turnbuckles 73. While the use of such rods complicates the folding and unfolding somewhat, it is obvious that they may be readily adjusted in length to effect the proper bracing of the parts.

It will be observed from the foregoing that my invention provides a simple, yet highly efficient boat of the semi-rigid folding type. The improved boat constitutes an improvement over folding or collapsible boats of the rigid type which are not only heavy but are cumbersome and are not readily reduced to small dimensions and also over boats of a flexible, non-rigid character which, in most cases, must be inflated and which deteriorate and leak. The present boat is adapted for general use and may be advantageously employed as an emergency lifeboat and included in the lifesaving equipment of larger vessels, airplanes and lifesaving squads.

While I have herein shown and described my foldable boat as embodied in a preferred form of construction, by way of example, it will be obvious that modifications may be made in the structure thereof without departing from the spirit of the invention. Consequently, I do not wish to be limited by the foregoing specification, but desire to be afforded the full scope of the appended claims.

I claim as my invention:

1. A foldable boat, including: a floor comprising a fore and an aft rigid floor section connected for relative pivotal movement on an axis extending transversely of the length of said boat; a gunwale comprising a fore and an aft rigid gunwale section connected for relative pivotal movement on a pivotal axis extending transversely of said boat; a waterproof flexible cover secured between said floor sections and said gunwale sections and providing therewith the sides, bow and stern of said boat; strut members pivoted on each of said floor sections and engageable with said gunwale sections to maintain said floor and said gunwale in spaced relation and to tension said flexible cover between said floor and said gunwale, said strut members being adapted to pivot to inoperative position against said floor sections to permit said gunwale and said floor to be moved toward each other, said fore and aft floor sections and said fore and aft gunwale sections being adapted to be pivoted on their respective pivotal axes to permit the fore and aft portions of said boat to be folded together in retracted relation and to be unfolded to extended relation; and operating means responsive to pivotal movement of said floor sections and said gun-

wale sections to extended position to pivot said strut members to operative position.

2. A foldable boat, including: a floor comprising a fore and an aft rigid floor section connected for relative pivotal movement on an axis extending transversely of the length of said boat; a gunwale comprising a fore and an aft rigid gunwale section connected for relative pivotal movement on a pivotal axis extending transversely of said boat; a waterproof flexible cover secured between said floor sections and said gunwale sections and providing therewith the sides, bow and stern of said boat; strut members pivoted on each of said floor sections and having free ends engageable with said gunwale sections to maintain said floor and said gunwale in spaced relation and to tension said flexible cover between said floor and said gunwale, said strut members being adapted to pivot to inoperative position against said floor sections to permit said gunwale and said floor to be moved toward each other, said fore and aft floor sections and said fore and aft gunwale sections being adapted to be pivoted on their respective pivotal axes to permit the fore and aft portions of said boat to be folded together in retracted relation and to be unfolded to extended relation; and operating means responsive to pivotal movement of said floor sections and said gunwale sections to extend position to pivot said strut members to operative position.

3. A foldable boat, including: a floor comprising a fore and an aft rigid floor section connected for relative pivotal movement on an axis extending transversely of the length of said boat; a gunwale comprising a fore and an aft rigid gunwale section connected for relative pivotal movement on a pivotal axis extending transversely of said boat; a waterproof flexible cover secured between said floor sections and said gunwale sections and providing therewith the sides, bow and stern of said boat; at least one pair of strut members pivoted on each of said floor sections and having free ends engageable with said gunwale sections to maintain said floor and said gunwale in spaced relation and to tension said flexible cover between said floor and said gunwale, said strut members being adapted to pivot to inoperative position against said floor sections to permit said gunwale and said floor to be moved toward each other, said fore and aft floor sections and said fore and aft gunwale sections being adapted to be pivoted on their respective pivotal axes to permit the fore and aft portions of said boat to be folded together in retracted relation and to be unfolded to extended relation; and operating means responsive to pivotal movement of said floor sections and said gunwale section to extended position to pivot said strut members to operative position.

4. A foldable boat, including: a floor comprising a fore and an aft rigid floor section connected for relative pivotal movement on an axis extending transversely of the length of said boat; a gunwale comprising a fore and an aft rigid gunwale section connected for relative pivotal movement on a pivotal axis extending transversely of said boat; a waterproof flexible cover secured between said floor sections and said gunwale sections and providing therewith the sides, bow and stern of said boat; at least one pair of strut members pivoted on each of said floor sections and having free ends engageable with the lower side of said gunwale sections to maintain said floor and said gunwale in spaced relation and to ten-

sion said flexible cover between said floor and said gunwale, said strut members being adapted to pivot to inoperative position against said floor sections to permit said gunwale and said floor to be moved toward each other, said fore and aft floor sections and said fore and aft gunwale sections being adapted to be pivoted on their respective pivotal axes to permit the fore and aft portions of said boat to be folded together in retracted relation and to be unfolded to extended relation; and operating means responsive to pivotal movement of said floor sections and said gunwale sections to extended position to pivot said strut members to operative position.

5. A foldable boat, including: a floor comprising a fore and an aft rigid floor section connected for relative pivotal movement on an axis extending transversely of the length of said boat; a gunwale comprising a fore and an aft rigid gunwale section connected for relative pivotal movement on a pivotal axis extending transversely of said boat; a waterproof flexible cover secured between said floor sections and said gunwale sections and providing therewith the sides, bow and stern of said boat; two pairs of strut members pivoted on each of said floor sections and having free ends engageable with the lower side of said gunwale sections to maintain said floor and said gunwale in spaced relation and to tension said flexible cover between said floor and said gunwale, said strut members being adapted to pivot to inoperative position against said floor sections to permit said gunwale and said floor to be moved toward each other, said fore and aft floor sections and said fore and aft gunwale sections being adapted to be pivoted on their respective pivotal axes to permit the fore and aft portions of said boat to be folded together in retracted relation and to be unfolded to extended relation; and operating means responsive to pivotal movement of said floor sections and said gunwale sections to extended position to pivot said strut members to operative position.

6. A foldable boat, including: a floor comprising a fore and an aft rigid floor section connected for relative pivotal movement on an axis extending transversely of the length of said boat; a gunwale comprising a fore and an aft rigid gunwale section connected for relative pivotal movement on a pivotal axis extending transversely of said boat; a waterproof flexible cover secured between said floor sections and said gunwale sections and providing therewith the sides, bow and stern of said boat; two pairs of transversely spaced strut members pivoted on each of said floor sections, the strut members on said fore floor section being adapted to be inclined upwardly and forwardly and the strut members on said aft floor section being adapted to be inclined upwardly and rearwardly and all of said strut members being engageable with said gunwale sections when so inclined to maintain said floor and said gunwale in spaced relation and to tension said flexible cover between said floor and said gunwale, said strut members being adapted to pivot to inoperative position against said floor sections to permit said gunwale and said floor to be moved toward each other, said fore and aft floor sections and said fore and aft gunwale sections being adapted to be pivoted on their respective pivotal axes to permit the fore and aft portions of said boat to be folded together in retracted relation and to be unfolded to extended relation; and operating means responsive to pivotal movement of said floor sections and said gunwale sections and said

gunwale sections to extended position to pivot said strut members to operative position.

7. A foldable boat, including: a floor comprising a fore and an aft rigid floor section connected for relative pivotal movement on an axis extending transversely of the length of said boat; a gunwale comprising a fore and an aft rigid gunwale section connected for relative pivotal movement on a pivotal axis extending transversely of said boat; a waterproof flexible cover secured between said floor sections and said gunwale sections and providing therewith the sides, bow and stern of said boat; two pairs of transversely spaced strut members pivoted on each of said floor sections, the strut members on said fore floor section being adapted to be inclined upwardly and forwardly and the strut members on said aft floor section being adapted to be inclined upwardly and rearwardly and all of said strut members being engageable with said gunwale sections when so inclined to maintain said floor and said gunwale in spaced relation and to tension said flexible cover between said floor and said gunwale, said strut members being adapted to pivot to inoperative position against said floor sections to permit said gunwale and said floor to be moved toward each other, said fore and aft floor sections and said fore and aft gunwale sections being adapted to be pivoted on their respective pivotal axes to permit the fore and aft portions of said boat to be folded together in retracted relation and to be unfolded to extended relation; connecting members pivotally connected between each two pairs of strut members; and tie members connected between the pairs of fore and aft strut members and the floor section opposite that to which said pairs of strut members are respectively pivoted.

8. A foldable boat as defined in claim 7 in which said connecting members include horizontal portions extending transversely of said boat and providing seats.

9. A foldable boat as defined in claim 7 in which said tie members consist of flexible straps.

10. A foldable boat as defined in claim 7 in which said tie members consist of rods pivotally connected between the pairs of fore and aft strut members and the floor section opposite that to which said pairs of strut members are respectively pivoted.

11. A foldable boat as defined in claim 7 in which said connecting members include horizontal portions extending transversely of said boat and providing seats and including brace members pivoted to said seats and adapted to be folded down against said floor sections.

12. A foldable boat as defined in claim 7 in which said connecting members include horizontal portions extending transversely of said boat and providing seats and including brace members pivoted to said seats and adapted to be folded down against said floor sections and brace members pivoted to the fore and aft ends of said gunwale and adapted to be folded down against said floor sections.

13. A foldable boat, including: a floor comprising a fore and an aft rigid floor section connected for relative pivotal movement on an axis extending transversely of the length of said boat; a gunwale comprising a fore and an aft rigid gunwale section connected for relative pivotal movement on a pivotal axis extending transversely of said boat; a waterproof flexible cover secured between said floor sections and said gunwale sections and providing therewith the sides, bow and

stern of said boat; strut members pivoted on each of said floor sections and engageable with said gunwale sections to maintain said floor and said gunwale in spaced relation and to tension said flexible cover between said floor and said gunwale, said strut members being adapted to pivot to inoperative position against said floor sections to permit said gunwale and said floor to be moved toward each other, said fore and aft floor sections and said fore and aft gunwale sections being adapted to be pivoted on their respective pivotal axes to permit the fore and aft portions of said boat to be folded together in retracted relation and to be unfolded to extended relation; operating means responsive to pivotal movement of said floor sections and said gunwale sections to extended position to pivot said strut members to operative position; and a detachable tie beam extending between said fore and aft floor sections.

14. A foldable boat, including: a floor comprising a fore and an aft rigid floor section connected for relative pivotal movement on an axis extending transversely of the length of said boat; a gunwale comprising a fore and an aft rigid gunwale section connected for relative pivotal movement on a pivotal axis extending transversely on said boat; a waterproof flexible cover secured between said floor sections and said gunwale sections and providing therewith the sides, bow and stern of said boat; strut members pivoted on each of said floor sections and engageable with said gunwale sections to maintain said floor and said gunwale in spaced relation and to tension said flexible cover between said floor and said gunwale, said strut members being adapted to pivot to inoperative position against said floor sections to permit said gunwale and said floor to be moved toward each other, said fore and aft floor sections and said fore and aft gunwale sections being adapted to be pivoted on their respective pivotal axes to permit the fore and aft portions of said boat to be folded together in retracted relation and to be unfolded to extended relation; connecting members pivotally connected between each two pairs of strut members; and tie members connected between the pairs of fore and aft strut members and the floor section opposite that to which said pairs of strut members are respectively pivoted.

15. A foldable boat as defined in claim 1 and including a plurality of longitudinally aligned loop members on said fore and aft floor sections; and a rod adapted to be inserted through said loop members to prevent folding of said floor sections.

16. A foldable boat as defined in claim 1 and including flexible sealing means between said fore and aft floor sections.

17. A foldable boat as defined in claim 1 and including a flexible strip of waterproof material extending between said fore and aft floor sections for sealing the bottom of said boat.

18. A foldable boat, including: a floor comprising a fore and an aft rigid floor section connected for relative pivotal movement on an axis extending transversely of the length of said boat; a gunwale comprising a fore and an aft rigid gunwale section connected for relative pivotal movement on a pivotal axis extending transversely of said boat; a waterproof flexible cover secured between said floor sections and said gunwale sections and providing therewith the sides, bow and stern of said boat; strut members pivoted on each of said floor sections and engageable with said gunwale sections to maintain said floor and said gunwale in spaced relation and to tension said

flexible cover between said floor and said gunwale, said strut members being adapted to pivot to inoperative position against said floor sections to permit said gunwale and said floor to be moved toward each other, said fore and aft floor sections and said fore and aft gunwale sections being adapted to be pivoted on their respective pivotal axes to permit the fore and aft portions of said boat to be folded together in retracted relation and to be unfolded to extended relation; and automatically operated means responsive to pivotal movement of said floor sections and said gunwale sections to extended position to pivot said strut members to operative position.

19. A foldable boat, including: a floor comprising a fore and an aft rigid floor section pivoted together; a gunwale comprising a fore and an aft rigid gunwale section pivoted together; a waterproof flexible cover extending between said floor sections and said gunwale sections, said waterproof cover being secured to both the floor sections and the gunwale sections and remaining so secured in both the folded and extended positions of said boat; and spacing means operative to maintain said floor and said gunwale in spaced relationship with said cover tensioned therebetween.

20. A foldable boat, including: a floor comprising a fore and an aft rigid floor section pivoted together; a gunwale comprising a fore and an aft rigid gunwale section pivoted together; a waterproof flexible cover extending between said floor sections and said gunwale sections, said waterproof cover being secured to both the floor sections and the gunwale sections and remaining so secured in both the folded and extended positions of said boat; releasable spacing means operative to maintain said floor and said gunwale in spaced relationship with said cover tensioned therebetween; and retaining means for releasably retaining said spacing means in operative position.

21. A collapsible boat structure, including: a gunwale formed of two rigid sections which are hinged to each other; a floor formed of two rigid sections which are hinged to each other; a waterproof flexible cover extending between said floor and said gunwale and forming therewith the sides, bow and stern of said boat structure, said waterproof cover being secured to both the floor and the gunwale and remaining so secured in both the collapsed and extended positions of said boat; and spacing means operatively connected between said floor and said gunwale and forming an integral part of said structure for maintaining said floor and said gunwale in spaced relationship with said cover tensioned therebetween.

22. A collapsible boat structure, including: a gunwale formed of two rigid sections which are hinged to each other; a floor formed of two rigid sections which are hinged to each other; a waterproof flexible cover extending between said floor and said gunwale and forming therewith the sides, bow and stern of said boat structure, said waterproof cover being secured to both the floor and the gunwale and remaining so secured in both the collapsed and extended positions of said boat; and spacing means pivotally connected be-

tween said floor and said gunwale and forming an integral part of said structure for maintaining said floor and said gunwale in spaced relationship with said cover tensioned therebetween.

23. A collapsible boat structure, including: a gunwale formed of two rigid sections which are hinged to each other; a floor formed of two rigid sections which are hinged to each other; a waterproof flexible cover extending between said floor and said gunwale and forming therewith the sides, bow and stern of said boat structure, said waterproof cover being secured to both the floor and the gunwale and remaining so secured in both the collapsed and extended positions of said boat; spacing means operatively connected between said floor and said gunwale and forming an integral part of said structure for maintaining said floor and said gunwale in spaced relationship with said cover tensioned therebetween; and retaining means for releasably retaining said spacing means in operative position.

24. A collapsible boat structure, including: a gunwale formed of two rigid sections which are hinged to each other; a floor formed of two rigid sections which are hinged to each other; a waterproof flexible cover extending between said floor and said gunwale and forming therewith the sides, bow and stern of said boat structure, said waterproof cover being secured to both the floor and the gunwale and remaining so secured in both the collapsed and extended positions of said boat; spacing means operatively connected between said floor and said gunwale and forming an integral part of said structure for maintaining said floor and said gunwale in spaced relationship with said cover tensioned therebetween; and adjustable retaining means for releasably retaining said spacing means in operative position.

25. A boat structure as defined in claim 21 in which said spacing means consist of strut members pivoted within said structure and including seat members carried by said strut members and pivoted therewith to operative and inoperative positions.

DONALD G. JACKSON.
